UNITED STATES PATENT OFFICE

2,533,784

DELIVERY MECHANISM FOR BOTTLE-WASHING MACHINES

Frederick H. Fruhling, Milwaukee, Wis., assignor to Continental Equipment Corporation, Milwaukee, Wis.

Application December 6, 1946, Serial No. 714,513

2 Claims. (Cl. 198—27)

1

My invention refers to bottle washing or soaking machines, wherein the bottles vary in size and are loaded into pockets of an endless conveyor, the generic principles of such machines being standard and are disclosed in Patent Number 2,024,373.

The primary object of my invention is to provide a cam controlled bottle loading mechanism having a forwardly pivoted bottle turning trough with a hinged bottle supporting plate at its forward receiving end, the said turning trough at its free end being normally aligned with a valve controlled spray pipe whereby a rinsing fluid jet is discharged into the mouth of a row of bottles. Thereafter the bottles are raised from the turning trough by reciprocative fingers and thereafter the bottles, by gravity, slide into a horizontally positioned loading trough, which trough is aligned with pockets of the intermittently traveling conveyor. The bottles or receptacles which are now practically drained of rinsing fluid, are then forced into a row of conveyor pockets preparatory to a soaking operation.

A further object of my invention is to provide a bottle turning trough carrying a pivoted plate upon which the bottom of the bottles rest and said plate, in a rocking movement of the trough, will tilt upwardly to guide the bottles in said trough.

With the above and other objects in view, which will appear as the description proceeds, the invention resides in the novel construction, combination and arrangement of parts, substantially as hereinafter described, and more particularly defined by the appended claims, it being understood that such changes in the precise embodiment of the herein disclosed invention may be made as come within the scope of the claims.

In the accompanying drawings is illustrated one complete example of the physical embodiment of the present invention constructed according to the best mode so far devised for the practical application of the principles thereof.

In the drawings:

Figure 1 represents a side elevation of the feed end of the bottle washer showing features of my invention.

Figure 2 is an enlarged fragmentary longitudinal sectional view through the bottle washer taken on the line 2—2 of Figure 4, looking in the direction of the arrows.

Figure 3 is a detail fragmentary longitudinal sectional view similar to Figure 2, but showing the bottle turning plate in its raised position for receiving a row of bottles.

2

Figure 4 is a horizontal sectional view taken on the line 4—4 of Figure 2, looking in the direction of the arrows.

Figure 5 is a detail fragmentary transverse sectional view taken through the machine on the line 5—5 of Figure 2, looking in the direction of the arrows, illustrating the rail for initially receiving a row of bottles and the supporting plate for the bottles.

10 Figure 6 is a fragmentary horizontal sectional view taken on the line 6—6 of Figure 3, looking in the direction of the arrows illustrating the bottle supporting plate and the bottle turning trough.

15 Figure 7 is a fragmentary transverse sectional view through the machine taken on the line 7—7 of Figure 2, looking in the direction of the arrows illustrating the bottle turning trough and the means for facilitating the ejection of the bottles from the turning trough to the discharge trough.

20 Referring to the drawings in detail, wherein similar reference characters designate corresponding parts throughout the several views, the numeral 1 indicates the feed end of a housing having mounted therein an endless conveyor 2 carrying rows of bottle holding pockets 3. The conveyor is supported upon a suitable track and is driven in any desired way.

The housing has mounted therein a rock shaft 4 carrying an arm 5 in link connection with a fingered ejector 6 normally aligned with one row of pockets 3, whereby the ejector fingers enter the mouths of the bottles and discharge the bottles from the pockets after a soaking operation onto an endless discharge conveyor 1. All of these parts are of standard construction and form no part of my present invention. Only sufficient parts of the bottle washing machine are shown and described to permit an understanding of my invention to be had.

40 In the upper front corner of the housing is mounted a cam shaft 8 in belt-drive connection with a motor 9 through which shaft and associated parts power or drive is imparted to all mechanism. The shaft 8 extends through the side walls of the housing and has secured thereto a cam 10 having a cam groove 11.

45 A cam arm 12 is rockably mounted upon a shaft 13 and said arm carries a roller 14 received in the cam groove 11, as best shown in Figure 1 of the drawings.

The front end of the housing is provided with the usual bottle inlet mouth 15. Pivottally mounted adjacent to the bottom of the feed mouth 15 is 55 a normally stationary guide and bottle supporting

rail 16, provided with suitable partitions for the reception of a row of bottles.

As best shown in Figures 1 and 2 of the drawings, the rail 16 is made yieldable under abnormal pressure and hence is provided with an arm 17 attached thereto at the pivot point thereof. A coil spring 18 is secured to the outer end of the arm 17 and to the housing and normally holds the rail against movement. However, the rail can yield under the tension of the coil spring in the event that jamming of the bottles upon the rail develops.

The housing has journaled therein a squared rock shaft 19, adjacent to the rail 16 and secured to said shaft is a suitably partitioned bottle turning trough 20, the same being provided with the slots 21 in its bottom face, as best illustrated in Figures 2, 3, 4 and 7 of the drawings.

The turning trough 20 adjacent to the shaft 19 has pivoted thereto a bottle supporting plate 22, which plate extends under the rail 16 and its free end is slidably supported upon a transversely extending guide rod 23.

The free or inner end of the bottle turning trough 20 is provided with a perforated bottle checking or stop strip 24 and, as illustrated, particularly in Figures 2, 3 and 4 of the drawings, the turning trough when in its normal position of rest is inclined downwardly. The perforated stop or checking strip 24, is disposed in front of an apertured spray pipe 25, when the bottle turning trough is in its lowered downwardly inclined position, as best shown in Figure 2. This pipe 25 carries an angle iron strip 26 and secured to and supported by this strip is a horizontally disposed guttered discharge trough 28, provided with a series of partitions 29 therein, whereby runways are formed for a series of bottles of any size. As shown, the inner end of the discharge trough 28 is in alignment with one row of conveyor bottle pockets 3.

As best illustrated in Figures 2, 4 and 7 of the drawings, the bottom slots 21 of the turning trough 20 are provided for the entrance therein of pairs of fingers 30, which fingers extend up from a U-shaped bridge piece 31. One end web of the bridge piece 31 has pivotally connected thereto a guide strap 32, and the upper end of the guide strap is slidably received and guided in a looped strap 33.

The down turned webbed ends of the bridge piece 31 are pivotally connected to rocker arms 34, which rocker arms are keyed or otherwise fastened to a transversely extending shaft 35 journaled in the side walls of the housing. The above described mechanism all refers to the travel of bottles from the mouth 15 of the housing to a row of conveyor pockets 3, whereby loading of the bottles on the conveyor 2 is effected. The operating means for the bridge piece 31 and the turning trough 20, etc., will be later described.

In a loading operation, it is apparent, as illustrated in Figure 2 of the drawings, that a row of bottles (indicated in dotted lines) is inserted in the housing through the mouth 15 against the rail 16 with their bottoms resting upon the plate 22. Under cam control to be hereinafter brought out, the bottle turning trough will swing upwardly upon its pivot, as indicated in dotted lines in Figure 2 of the drawings, and in full lines in Figure 3, to a position adjacent to the rail 16 and in its upward swing, the rocking bottom plate 22 carried by the turning trough will move under and inward of the rail 16 and the forward end thereof will lower and the outer or free end

thereof will be raised and the bottles will be caused to fall into the bottle turning trough 20 (see Figure 3). In the next step, the bottle turning trough will swing downwardly to its normal position of rest, as indicated in full lines in Figure 2. In this downward swing, the row of bottles carried by the trough will slide toward the bottle checking or stop strip 24 and the mouths of the bottles will be aligned with the apertures in the strip and the spray openings of the pipe 25. At this time, liquid will be supplied to the pipe 25 and jets of rinsing liquid will be discharged into the bottles so that the bottles will be thoroughly pre-rinsed during their loading travel.

In the next operation, the rocker arms 34 and fingers 36 of the bridge piece 31, will move upwardly, whereby the fingers will pass through the slots in the trough 20 and lift the row of bottles upwardly and position the same over the adjacent end of the horizontal bottle discharge trough 28 and said row of bottles will then slide into the trough 28 and come to rest upon the bottom of said trough.

As shown in Figures 2 and 4 of the drawings, the bottom of the discharge trough 28 is provided with a series of longitudinally extending slots for the reception of tongues or fingers 36 extending from legs 37. These legs are keyed or otherwise secured to a rock shaft 38 journaled in the walls of the housing.

To complete the bottle loading movement, when the row of bottles, as indicated in dotted lines in Figure 2, is resting upon the floor of the trough 28, the discharge legs 37 with their associated fingers or tongues 36 move from left to right in an arc of a circle, whereby the tongues or fingers 36 will enter the trough slots and engage the rear ends or the bottoms of the bottles to cause them to be discharged into a row of conveyor pockets 3.

The lever mechanism for actuating the bottle turning trough 20 and associated parts, as best indicated in Figure 1 of the drawings, includes a lever 39 secured to one end of the rock shaft 19. The lever 39 is connected by a link 40 to the extreme upper end of an arm 41 and this arm 41 in turn is connected intermediate its ends by a link 42, to one arm of a bell crank lever 43. The bell crank lever 43 is secured to and mounted upon one end of the shaft 4, which shaft intermediate its ends carries the ejector mechanism arms 5. Motion is imparted to the bell crank lever 43 by a rod 44 in pivotal connection with one arm of the bell crank 43 and the cam actuated arm 12.

The supply of rinsing fluid to the spray pipe 25 is controlled by a valve 45. The valve is of the type normally held closed under spring pressure. This valve 45 carries a pivoted link 46 connected by a rod 47 to a crank lever 48 that is pivoted to the housing wall adjacent to the face of the cam 10. The link 46 actuates the valve against tension of its spring, when the link is moved inwardly. The periphery of the cam 10 has extending therefrom a cam shoe or lobe 49, which shoe in its rotation engages a roller 50 carried by the crank arm 48, whereby said crank arm and its connections will actuate the link and the valve. At the time, the mouths of the bottles are in alignment with the apertures of the pipe 25, the valve 45 will be open and water will be sprayed into the bottles.

To operate the bridge piece 31 and its fingers 36 the shaft 8 can be provided with a cam 51.

The cam 51 is on the opposite end of the shaft 8 from the cam 10 and this cam 51 actuates an arm 52 rockably mounted upon the shaft 13. The arm 52 actuates a rock shaft 53 through the medium of a link 54 pivoted to the arm 52 and a crank 55 secured to the rock shaft 53. A second crank 56 is secured to the rock shaft 53 and this crank 56 is operatively connected to the shaft 35 by means of a link 57. The link 57 is pivotally connected to the crank 56 and to a crank 58 secured to the shaft 35. At the proper time, the crank 56 will be operated and the arms 34 will be raised and the fingers 30 will perform their function of elevating the bottles in the bottle turning trough 20 to cause the bottles to slide into the trough 23.

From the foregoing description, it can be seen that a novel mechanism is provided for insuring the proper delivery of a row of bottles to a row of pockets in a bottle conveyor.

Changes in details may be made without departing from the spirit or the scope of this invention but what is claimed as new is:

I claim:

1. In a bottle washing machine, a bottle delivery mechanism including a horizontally disposed discharge trough, a bottle turning slotted trough pivoted above the discharge trough, a bottle supporting oscillatory plate in pivotal crank connection with the axis of the bottle turning trough, a fixed guide rod for supporting the free end of the oscillatory plate, whereby a bottle may be seated on the plate, cam controlled lever actuating means for rocking the bottle turning trough upward upon its axis, whereby the free end of the oscillatory plate is lifted upwardly upon its guide rod to cause the bottle to be tilted backwardly into the bottle turning trough, the said bottle turning trough being thereafter rocked down-

wardly to a bottle discharging position relative to the discharge trough, and cam controlled lever actuated fingers movable in the slots of the bottle turning trough to deliver a bottle into the discharge trough.

2. In a machine of the character described, a bottle delivery mechanism therefor, comprising a fixed rail adapted to support a bottle, a bottle turning trough pivoted in juxtaposition to the rail, a supporting plate positioned under said rail and in pivotal connection with the trough, the said pivotal connection being offset from the trough axis, and a guide for the free end of the plate, whereby when the trough is oscillated towards the rail, the supporting plate will be tilted upwardly, whereby the bottle is shifted backwardly into the aforesaid trough.

FREDERICK H. FRUHLING.
